UNITED STATES PATENT OFFICE.

LUCIUS J. PHELPS, OF LOS ANGELES, CALIFORNIA, ASSIGNOR TO WILLIAM J. HUMPHREYS, OF SAN GABRIEL, CALIFORNIA.

HOMOGENIZER.

1,423,488.

Specification of Letters Patent. Patented July 18, 1922.

Application filed May 19, 1921. Serial No. 470,926.

To all whom it may concern:

Be it known that I, LUCIUS J. PHELPS, a citizen of the United States, residing at Los Angeles, in the county of Los Angeles and State of California, have invented new and useful Improvements in Homogenizers, of which the following is a specification.

This invention is an attachment employed in connection with internal combustion engines, and providing means disposed within the intake manifold of the engine for impingement by the combustible mixture passing through the intake manifold so as to break up said mixture and thereby cause complete vaporization of the fuel.

More specifically the invention provides impingement elements, one of which functions within the intake manifold just beyond the carburetor so as to cause initial breaking up of the vaporized mixture. A second impingement element is provided in the transversely extending portion of the intake manifold which leads to the respective cylinders, said element extending across the perpendicularly disposed portion of the manifold so as to be impinged by all of the combustible mixture flowing through the manifold. The breaking up of the combustible mixture will be completed by the second impingement element, and as a consequence thorough vaporization of the fuel will occur.

The invention will be readily understood from the following description of the accompanying drawings, in which:

Figure 1 is a side elevation of an internal combustion engine showing the intake manifold partially broken away and having the attachment positioned within said intake manifold.

Figs. 2 and 3 are detail transverse sections on the lines 2—2 and 3—3 of Fig. 1.

The attachment is employed in connection with a usual engine construction including carburetor 1 having flanged coupling member 2 to which the intake pipe 3 is connected by a co-operating flange coupling 4. The intake manifold includes a usual horizontally disposed portion 3^a communicating with a vertical portion 3^b which in turn communicates with a transverse extension 3^c leading to the respective cylinders of engine 5.

The attachment forming the present invention includes two impingement elements preferably formed of metallic screening of

suitable mesh. One of these elements comprises a conical structure as shown at 6 and preferably formed of a single sheet of screening wrapped upon itself so as to form a cone having an open base and a closed apex. A metallic stiffening ring 9 is preferably received within the open base of the conical screen. The cone is mounted in the portion 3^a of the intake manifold with the base of said cone received against the usual beveled lip 10 at the coupling flange 4 of the manifold, and by this arrangement it will be seen that when coupling flanges 2 and 4 are secured together, the impingement elements will be supported in the intake manifold.

The apex of the cone extends in the direction of flow of the combustible mixture through the intake manifold and may be curved to conform to the curvature of the intake manifold as it is extended to form the portion 3^b thereof. By this arrangement it will be seen that all of the combustible mixture will enter the cone 6 and must pass through the screening forming the same during its flow through the intake manifold, and as a consequence the mixture will be broken up so as to increase the vaporization thereof.

A second impingement element is provided in the transverse portion 3^c of the manifold, and preferably includes a screen which is transversely bent and rebent so as to form the angularly spaced portions 12 of said screen, which form a structure adapted to be readily received in the transverse portion of the manifold over the opening from the same to the vertically disposed portion 3^b of the manifold. By this arrangement it will be seen that the combustible mixture entering the transverse portion of the manifold will abut against portions 12 of the impingement element during the passage thereof to the engine cylinders, and as a consequence the vaporization of the fuel will be increased so as to form a more efficient combustible mixture.

Various changes may be made without departing from the spirit of the invention as claimed.

What is claimed is:

1. The combination with an internal combustion engine including an intake manifold having a flanged coupling end and including a transverse portion communicating with

a perpendicular extension, of an impingement element in said manifold for breaking up the combustible mixture and including an annulus clamped in position by said 5 coupling flange for supporting said impingement element, and a second impingement element for breaking up the combustible mixture and received in said transverse portion of the manifold so as to extend across 10 the perpendicular extension of said manifold.

2. The combination with an internal combustion engine including an intake manifold having a transverse portion communicating 15 with a perpendicular extension, of an impingement element for breaking up the combustible mixture and including a screen transversely bent and rebent to form angu-

larly disposed superimposed layers, said screen being received in said transverse portion of the manifold so as to extend across 20 the perpendicular extension of said manifold.

3. An impingement element of the character described comprising a screen transversely bent and rebent to form angularly disposed superimposed layers. 25

4. An impingement element of the character described comprising foraminous material recurrently bent transversely to provide superposed layers which gradually decrease in width from the innermost layer. 30

In testimony whereof I have signed my name to this specification.

LUCIUS J. PHELPS.
